CLAIM

The ornamental design of the pillow, as shown and described.

DESCRIPTION

FIG. 1 is a front perspective view of the pillow, showing my new design.

FIG. 2 is a front elevational view thereof.

FIG. 3 is a rear elevational view thereof.

FIG. 4 is a right side view thereof.

FIG. 5 is a left side view thereof.

FIG. 6 is a top view thereof; and,

FIG. 7 is a bottom view thereof.

The broken lines shown in the drawings represent unclaimed portions of the design and form no part thereof.
